(57) **CLAIM**

The ornamental design of a support block and clip assembly, as shown and described.

DESCRIPTION

FIG. 1 is a perspective view of a support block and clip assembly;

FIG. 2 is a front elevation view thereof;

FIG. 3 is an opposing elevation view of FIG. 2;

FIG. 4 is a side view thereof;

FIG. 5 is an opposing side view of FIG. 4;

FIG. 6 is a top plan view thereof; and,

FIG. 7 is a bottom plan view thereof.

The portions of the support block and clip assembly shown in broken lines form no part of the claimed design.
